GEORGE J. MORRIS, OF LOS ANGELES, CALIFORNIA, ASSIGNOR TO GEORGE E. MORRIS,
OF LOS ANGELES, CALIFORNIA.

FAUCET FITTING.

Application filed February 23, 1927. Serial No. 170,312.

My invention relates to water faucets as used in connection with sinks, bath tubs and the like, and particularly to the multiple valve type in which various kinds of water 5 can be discharged from a single nozzle.

It is a purpose of my invention to provide a faucet of the above described character which eliminates the necessity of employing and extending through a sink or tub separate 10 feed pipes for the various kinds of water used, and the attendant disadvantages of manufacture and installation, and expense, all by the provision of a fitting having a single feed pipe divided longitudinally into a plurality 15 of passages, one for each kind of water used, with the necessary valves for separately controlling the discharge of water from each passage to a single nozzle.

It is also a purpose of my invention to provide 20 a faucet fitting of the multiple type in which the discharge nozzle is movable to a position in which it discontinues the discharge of water therefrom and in a manner to cause the water to be discharged from a subsidiary 25 port for use as a shower or any other purpose.

A further purpose of my invention is the provision of a faucet fitting having a covering sleeve for the pipe thereof and an escutcheon plate with means by which they may be firmly 30 clamped in proper position when the fitting is applied to a single tub.

I will describe only two forms of faucet 35 fittings embodying my invention, and will then point out the novel features thereof in claims.

In the drawings

Figure 1 is a view showing in horizontal section one form of faucet fitting embodying my invention;

Figure 2 is a vertical sectional view taken on the line 2--2 of Figure 1, the discharge nozzle having been rotated through an arc of 90°;

Figure 3 is a fragmentary view showing in side elevation a portion of the discharge nozzle embodied in the fitting;

Figure 3a is a detail view of one of the washers employed in the fitting shown in Figure 1;

Figure 4 is a view similar to Figure 1, showing another form of faucet fitting embodying my invention;

Figure 5 is a view showing in front elevation and partly in section the faucet fitting shown in Figure 4;

Figure 6 is a sectional view taken on the line 6--6 of Figure 4.

Referring specifically to the drawings, and particularly to Figures 1, 2 and 3, my invention in this embodiment comprises a metal body which includes a suitable length of pipe 60 P merging at one end into a transverse pipe P', which latter provides a pair of connecting nipples 15 and 16 interiorly threaded for connection to a pair of water supply pipes (not shown), and which pipes may be designed to 65 supply hot and cold water to the body. The pipe P is exteriorly threaded as shown in Figure 1 and is adapted to extend through the apron of a sink or the end wall of a tub, a partition T being shown in Figure 1 to illustrate either of these elements. In the applied position of the pipe to the partition the pipe P' is disposed at the inner side or the wall side 70 of the partition, and that portion of the pipe P projecting to the outer side of the partition 75 is covered with a finishing sleeve S upon which is mounted an escutcheon plate E, with the sleeve provided with an annular rib 17 for confining the plate in contiguous relation to the partition, as illustrated. A nut D is 80 threaded on the pipe P at the opposite side of the partition T so as to secure the pipe in fixed longitudinal position within the partition, as will be understood. The sleeve S in turn is secured against longitudinal movement by 85 means of a ring 18 threaded on the pipe P and engaged by a flange 19 of a connecting collar 20.

The body of the fitting also includes a spherical head H provided with a nipple 21 90 exteriorly threaded so as to be engaged by the interiorly threaded collar 20 and to thereby rigidly mount the head and the elements carried thereby upon the pipe P. As clearly shown in Figure 1, the pipes P and P' are 95 provided with a partition 22 which extends lengthwise of the pipe P and transversely of the pipe P' to divide the two into a pair of separate water chambers, the nipples 15 and 16 constituting the inlet ends of the passages 100 and the outlet ends of the passages being in communication with similar passages provided by partitions 23, 24 and 25 in the head H.

To form a water-tight joint between the 105 nipple 21 and the pipe P, a washer W is interposed between the confronting ends of the two. As shown in detail in Figure 3a, the

washer is annular in form, with a diametrically disposed portion w to be interposed between the confronting ends of the partitions 22 and 23, and positioning pins w' engaging within recesses in the nipple 21 to fix the washer against circumferential displacement. The threads on the pipe P are left hand while those on the nipple 21 are right hand, so that when the collar 20 is screwed on the nipple it slightly feeds the ring 18 inwardly on the pipe P, thus forcing the sleeve S toward the plate E and thereby causing the bead 17 to hold the plate in firm contact with the sink or tub wall.

13 The partitions 24 and 25 are provided with ports 24^a and 25^a, respectively, through which water from the respective passages is discharged into the head for subsequent distribution from a nozzle N. These ports are controlled by valves 26 and 27 respectively on stems 28 and 29 threaded in nipples 30 of the head H and provided with handles 31 by which the valves can be manually adjusted to close or open the ports. The head H is also provided with a relatively long and vertically disposed extension 32 in which is threaded the tubular elongated stem 33 of the nozzle end, the stem being confined against displacement by a cap 34 threaded on the lower end of the extension and provided with a gasket 35 to render the joint between the extension and the cap watertight. The stem provides a mounting for the nozzle N to permit it to be rotated from the forwardly extending position shown in Figure 1 to the ninety degree lateral position shown in Figure 2.

By referring to Figure 2, it will be clear that the partitions 23, 24 and 25 are spanned at the top and bottom to form a structure which may be considered as independent of the spherical head H. This structure is provided at its under side with a ground surface 36 against which the upper end of the stem 33 is adapted to abut when the nozzle end is in the right angular position shown in Figure 2, so that such structure functions to close the stem and thereby discontinue the discharge of water from the nozzle. When the nozzle is in this position water leaving the ports 24^a and 25^a, assuming that the valves 26 and 27 are in open position, will pass outwardly of the head H through an opening 37 and into a pipe 38. This pipe 38 may constitute a water spraying device such as is used in connection with bath tubs for showering. It will of course be understood that should it not be desired to use a spraying device, the pipe 38 can be removed and a plug (not shown) screwed into the opening for closing the latter.

In practice, the hot and cold water supply pipes adapted for connection with the nipples 15 and 16 function to supply hot and cold water, respectively, to the two chambers of

the pipe P and from the latter to the two chambers of the head H. The discharge of water from the head chambers is of course controlled by the valves 26 and 27, and when such valves are opened the water will be discharged into the head, intermixing therein and finally discharging from the nozzle end, assuming that the latter is in the position shown in Figure 1. The amount of cold water or hot water can be regulated by an adjustment of the valves 26 and 27 so as to secure at the nozzle water of any desired temperature. If it is desired to discharge the water from the fitting through the pipe 38, the nozzle end is moved to the right angle position shown in Figure 2 to cause the upper end of the stem 33 to engage the seat 36 as has been described.

Referring now to Figures 4, 5 and 6, I have here shown another form of faucet fitting embodying my invention, which is designed for the separate reception and conduction of three kinds of water to the fitting head where, if desired, an intermixing of the three waters is effected before finally discharging from the nozzle. In this form of my invention a pipe P² is provided corresponding to the pipe P of the first form of my invention, and mounted on one end of this pipe is a T-shaped pipe P³. The pipe P² is provided interiorly with three partitions 39 extending longitudinally and dividing the latter into three separate passages. Likewise the pipe P³ is provided with three partitions 40 so arranged as to form passages which communicate with the respective passages of the pipe P². The three nipples of the pipe P³ are adapted for connection to water supply pipes so as to receive respectively hot, cold and soft water. The pipe P² is connected to a nipple 41 of a fitting head H' by means of a collar 42 and in the same manner as the connection between the pipe P and the head H in the first form of my invention. The head H' is provided with a rectangular structure in the same manner as the head H and this structure is divided interiorly into three separate passages by means of partitions 43 as clearly illustrated in Figure 5. The structure is also provided with ports 44, 45 and 46 controlled by valves 47, 48 and 49, respectively. Through these ports the respective waters are discharged into the head and ultimately from the nozzle N'.

In this form of my invention the several passages in the pipes and head provided by the partitions serve to separately conduct the different waters to the head, the separate discharge of the waters into the head being controlled by an adjustment of the respective valves. In this manner any combination of waters can be discharged from the nozzle and in any proportions desired.

Although I have herein shown and described only two forms of faucet fittings em-

bodying my invention, it is to be understood that various changes and modifications may be made therein without departing from the spirit of my invention, and within the spirit 5 and scope of the appended claims.

I claim:

1. In a faucet fitting, a pipe having thereon a sleeve, a projection on the sleeve, an escutcheon plate on the sleeve engaged by the 10 projection for holding the latter in fixed relation to a partition, and a ring on the pipe engaging the sleeve for the purpose described.
2. In a faucet fitting, an externally threaded pipe having thereon a sleeve, an annular 15 projection on the sleeve, an escutcheon plate on the sleeve adapted to be engaged by the projection for holding the sleeve in fixed relation to a partition, and a ring threaded on the pipe and adapted to engage the sleeve 20 for the purpose described.
3. In a faucet fitting, a head having a threaded portion, a pipe having a sleeve thereon, a projection on the sleeve, an escutcheon plate on the sleeve for holding the sleeve 25 in fixed relation to a partition, said pipe being threaded externally and oppositely from the threads of the head, a ring threaded on the pipe and adapted to engage the sleeve, and a threaded coupling collar adapted to 30 engage the ring and threads of the head for connecting the pipe and head, said collar adapted when screwed onto the head to tend

to rotate the ring on the pipe into engagement with the sleeve by virtue of the opposed threads on the head and pipe. 35

4. In a faucet fitting, an externally threaded pipe adapted to be extended through a wall and to be cut off to project a predetermined distance from the wall, a nut on the pipe adapted to engage one side of the wall, 40 an escutcheon plate having an opening receiving the pipe and adapted to engage the other side of the wall, a finishing sleeve on the pipe having a projection adapted to engage the escutcheon plate for limiting movement of the sleeve towards the plate, a ring threaded on the pipe adapted to abut the sleeve when positioned flush with the projecting end of the pipe and operating to clamp the pipe to the wall, a head having a portion 50 threaded oppositely from the threads of the pipe, and a threaded coupling collar on the pipe adapted when screwed on the head to engage the ring and thereby draw the pipe and head together. 55

5. In a faucet fitting, a pipe, an escutcheon plate having an opening receiving the pipe, a sleeve on the pipe having means adapted to engage the escutcheon plate to maintain the sleeve in fixed relation to a partition, and 60 means on the pipe adapted to engage the sleeve for the purpose described.

GEORGE J. MORRIS.
